CLAIM

The ornamental design for a palm-held liquid and lotion applicator, as shown and described.

DESCRIPTION

FIG. 1 is a front elevation of a palm-held liquid and lotion applicator showing my new design, the rear elevation is the same except for the continuous screw threading on the neck;

FIG. 2 is a perspective view thereof;

FIG. 3 is a right side elevation thereof, the opposite side elevation is the same except for the continuous screw threading on the neck;

FIG. 4 is a front elevation of a second embodiment of the palm-held liquid and lotion applicator;

FIG. 5 is a left side elevation of the second embodiment, the right side elevation is a mirror image thereto except for the continuous screw threading on the neck;

FIG. 6 is a perspective view of the second embodiment; and,

FIG. 7 is a rear elevation of the second embodiment.
